UNITED STATES PATENT OFFICE

LEWIS F. MOODY, OF PHILADELPHIA, PENNSYLVANIA

TURBINE APPARATUS

Application filed April 13, 1927. Serial No. 183,293.

This invention relates to hydraulic impulse or free jet turbines of the type wherein actuating fluid is discharged entirely to one side of the rotor, and to impulse turbines particularly adapted to a vertical shaft setting.

One object is to provide a waterwheel of the impulse type which, while having buckets of moderate or low specific speed when used with a single jet, will at the same time have a high specific speed for the complete unit by employing a considerable number of jets, at the same time attaining high efficiency. A further object is to provide an improved form of low or moderate specific speed bucket adapted to receive a complete free jet of preferably cylindrical form.

In another phase of the invention an object is to provide an improved arrangement and means for controlling and directing fluid flow to the buckets. More specific objects in this respect are to provide an improved nozzle control and an improved relation between the main supply pipe or casing and the branches leading therefrom to the nozzles.

In a still further phase of the invention an object is to provide a multi-runner vertical shaft impulse turbine. A further object is to provide an arrangement of runners whereby all or part of the actuating fluid for the upper runner is discharged downwardly without interfering with the operation of, or fluid flow relative to, the lower runner or runners. A further and more specific object is to provide suitable deflecting means between the runners and to have a novel form of discharge passage for the upper runner with means associated therewith for suitably controlling pressure in said passage, thereby to effect control of the level of the water discharged from both runners and particularly for the lower runner in order to permit the latter to run clear of the tail water surface.

Other objects and advantages will appear from the following description of the accompanying drawings, in which

Fig. 1 is a vertical section of a single runner impulse turbine and showing parts of one form of my improved fluid controlling arrangement, certain parts thereof being shown in elevation.

Fig. 2 is a sectional plan view taken on line 2—2 of Fig. 1.

Fig. 3 is a modification showing a multi-runner vertical shaft turbine and having incorporated therein a modified fluid controlling arrangement.

Fig. 4 is a partial sectional view of the multi-runner turbine having further modified means and arrangement of parts for conducting and controlling actuating fluid to the turbine.

Fig. 5 is a front vertical elevation of my improved bucket which is adapted for use with either turbine arrangement.

Figs. 6, 7 and 8 are sectional views thereof taken on their respective lines in Fig. 5.

Fig. 9 is a longitudinal sectional view of my improved nozzle, taken substantially on line 9—9, of Fig. 10.

Fig. 10 is a transverse section taken on line 10—10 Fig. 9.

Fig. 11 is a partial vertical sectional view showing a modified form of turbine.

In the illustrated embodiment of my invention as shown in Fig. 1, a usual generator 1 is driven by a vertical shaft impulse runner 2 comprising a hub having a radial member or crown 3, this crown carrying a series of buckets 4 upon which one or a series of jets impinge. In general the jets are preferably of the solid or free cylindrical type disposed in a plane substantially normal to the runner axis. Variations in the shape of the jet will not depart from the idea of having independent or separate jets which constitute generally partial admission means, that is, fluid is admitted to the runner only on a part of its circumference.

Heretofore, buckets for impulse turbines of the type that discharge entirely to one side of the rotor, have been variously shaped and arranged in an attempt to find a form of bucket suitable to give a desired specific speed with a high degree of efficiency. In some instances, the prior buckets have been so shaped or arranged that they merely project radially from a surface of revolution formed on the runner hub. The result is that a complete bucket is not formed in the sense of my present invention, for this surface of revolution

generally extends transversely of the radial axis of the bucket. In other instances of prior turbine art of the general type herein considered and including patents of my own, the impulse buckets have been designed to receive only a part of a complete jet which usually is of annular hollow formation impinging on all buckets simultaneously.

In my present invention each bucket is adapted to receive the complete jet and discharge the same entirely to one side of the rotor, the buckets being formed so as primarily to receive a free jet of substantially cylindrical form. Also the fluid receiving surfaces of the buckets are such that said surfaces are independent of the shape or form of the bucket supporting means or any surface of revolution formed on the hub, thus causing each bucket to be an independent unit.

As shown in Figs. 5 to 8, each bucket preferably comprises a supporting portion 5 having lugs 6 projecting upwardly therefrom for attachment to the crown 3 as by suitable means such as bolts, screws or the like. If desired the bolt holes in the crown plate may be enlarged or shaped to permit angular adjustment of each bucket in a horizontal plane. The buckets proper depend from the supporting portion 5 and as shown in Fig. 5 both by the contour lines I to VIII and the bucket structure, the latter is of generally ellipsoidal form, although there are many other distinguishing features. For instance, one feature is in having the discharge edge 7 disposed either back of or terminating generally in a plane containing substantially the foremost part of the upper edge or entrance portion 8 of the bucket. The part of the support 5 projecting forwardly from this plane does not constitute, in the position of the jet as shown, a part of the fluid receiving surface of the bucket so that it might generally be said that the upper and lower front edges lie in substantially the same vertical plane which is indicated by section line I in Fig. 6. Also as shown in Fig. 6 the fluid receiving surface along a central vertical section, as on the line 6-6 of Fig. 5, is substantially circular, there being, however, a slight difference in the curvature in the upper and lower half, in that the centers for the respective radii are at x and y . In various horizontal sections, the bucket has surfaces as generally shown in Figs. 7 and 8, and in considering these sections, it will be noted that the major portion of the fluid surface 9 is curved, this being in distinction to certain prior buckets having relatively long and straight surfaces or elements and which

usually merge with small curved portions or fillets near the inner and outer radial limits of the bucket. For instance, it will be seen that the bucket is continually curving forwardly from a line $a-a$ or radially inward 63 from the line $b-b$ and also radially outward

from the line $c-c$. This curving characteristic is also true when the bucket is considered in vertical section as shown in Fig. 6. To permit proper entrance of the fluid, an entrance opening or cut-away portion 10 is formed in the outer part of the upper half of the bucket, but it will be noted that the entrance edge 11 of the bucket extends substantially to the outermost radial portion of the bucket instead of being disposed radially inward from said edge for any substantial distance as has been done in certain prior devices. A portion of the fluid receiving surface extending radially inward from edge 11 does not have as an acute degree of curvature as other portions of the fluid surfaces. Thus considering the bucket in horizontal section, the fluid surfaces are not only substantially continuously curving, but also the degree of curvature varies when considering the bucket from the innermost to the outermost radial portions thereof, or when considering the bucket from its rearmost to its foremost portions. In vertical section or elevation a somewhat similar construction is had, although for a short distance the lowermost portion of the discharge edge 7 is substantially straight, while it will be noted from the contour lines that as the fluid surface recedes from the discharge edge 7, a generally ellipsoidal form is assumed.

From the above, it is seen that there has been provided an improved form of bucket of a type particularly adapted to receive a substantially cylindrical free jet, which is discharged entirely to one side of the rotor or runner and that said bucket has its discharge edge 7 disposed substantially in the same plane containing the entrance edge of portion 8, thereby permitting discharge of the actuating fluid so as to be conducive to high efficiency and moderate specific speed when computed for a single jet.

As seen in Fig. 2, the buckets are angularly disposed to the runner radius, the entrance edge leading the inner radial portion of the bucket during rotation of the runner. The number of buckets shown are conducive to relatively low specific speeds while if a higher specific speed is desired the number of buckets would be increased. In fact in some instances the buckets would be so closely spaced that a meridian plane through the runner axis would pass through two successive buckets. The nozzles are so arranged, that a substantially tangential relation is obtained and the jet or jets will impinge upon the buckets substantially in the position as shown in Figs. 5 and 6. The entrance portion of the bucket as shown in Fig. 7 is adapted for a direction of entrance of the water relatively to the revolving runner which differs but little from a radial direction even though the entrance portion of the bucket points somewhat backwardly with respect to

the forward motion of the bucket. This is shown in the velocity diagram on Fig. 2, wherein the absolute velocities of the runner and jet and the velocity of the jet relative to the runner, are indicated respectively by U, C and W.

In another phase of my invention I have shown a multi-runner vertical shaft impulse turbine wherein the fluid flow acting on each runner does not interfere with the flow acting on the other runner. In one specific aspect of the invention, such as shown in Fig. 3, an upper runner 15 is secured to a suitable shaft 17 connected to a generator 18 and supported by suitable bearings including one at 17^a. Carried on the shaft below this latter bearing is a second runner 19 herein shown as identical to the upper runner, although under certain circumstances such as in a large unit under relatively low head the same might have certain variations therefrom such as in the type of bucket or size of runner to adapt it for the slightly greater head, for example, this being shown in Fig. 11 wherein the lower runner 19 is larger than the upper runner 15, the remaining turbine structure being identical to that shown in Fig. 3. The turbine buckets are preferably identical to those shown in Figs. 5 to 8, but the general arrangement of turbine runners and the elements co-operating therewith are not, of course, limited to the use of my present type of improved bucket.

A suitable deflector, which is specifically shown in the form of a cone 20, is supported upon an annular member 21 which in turn is supported by suitable ribs 22 connected to an outer wall 23. This whole structure is suitably supported upon a ring 24 or otherwise suitably embedded in or surrounded by a concrete structure. The cone 20 serves not only as a deflector but also as a suitable housing for the bearing 17^a thereby preventing dilution of the lubricant by water. The deflector may also take any other form desired, so long as it accomplishes the function of preventing water discharged from the upper runner falling upon the lower runner or into the jets therefor or being deflected back upon the upper runner to interfere with its action. The cone 20, member 21 and wall 23 form a chamber *a* communicating with a tail water passage *b* through a substantially annular passage 25. The admission of air to chamber *a* is suitably controlled as by a valve controlled pipe 26 thereby to control the pressure in this chamber so as to control the elevation of the free water surface in the passage *b*. This is for the purpose of insuring that the lower runner will run free of the tail water surface.

The other phase of the invention may be divided into the nozzle construction and the arrangement between the main conduit or supply casing and the branches leading there-

from to the nozzles. This arrangement, and also the improved nozzle, are applicable to either the single or double runner turbines, as shown in Figs. 1, 2 and 4. Heretofore, various arrangements have been employed for supplying fluid to the nozzles, but in each case the constructions have necessitated a tortuous flow passage. By my improved arrangement, however, angularities in the flow are reduced to a minimum, and accordingly not only may a higher efficiency be had, but also a simplified construction. As shown in Fig. 2, a spiral casing or conduit 30 encircles the runner and leading from this pipe at circumferentially disposed points are branches 31 while the last nozzle is supplied through an elbow 32 forming a continuation of the end of the supply conduit. It will be noted that the branches gradually curve, without reversals of curvature, from the main pipe 30 thereby insuring smooth flow lines. The distinguishing feature of this construction is, however, better seen by considering Fig. 1, wherein it will be noted that the nozzles 33 are disposed substantially in the plane of the supply conduit or spiral casing 30 and which is also true of the branches 31. Hence, the latter do not bend downwardly away from the supply conduit and which would necessitate introduction of an additional bend therein. The result is that only a single bend is employed, and this is substantially in a single plane.

Combined with this improved branch arrangement is the improved nozzle. As a result of the nozzle construction there is eliminated any need for having controlling elements extend rearwardly through the flow conduit or branch pipes. It is thus possible, with my improved form of nozzle, to provide various arrangements of branch pipes without being compelled to limit such arrangements in accordance with the nozzle construction.

My improved nozzle construction comprises a casing 60, suitably connected to the branch pipe 31, and a tapering end piece 61 having an orifice 62. Fluid through the orifice is controlled by a movable needle 63 shaped to co-operate with the particular shape of orifice. The rear end of the needle comprises a hollow portion 64 slidably disposed in an internal casing or cylinder 65 which through radial webs 66 is supported by the outer casing in spaced relation thereto, thereby forming an annular fluid passage A. A stationary piston rod 67 extending through an opening in the rear end of member 64 is fixed at one end to casing 65 and carries at its other end a piston 68 which cooperates with the hollow portion of member 64 to form a piston and cylinder arrangement for effecting closing movement of the cylinder.

Restoring mechanism associated with the nozzle includes a collar 69 secured to member 130

64 and having slots on opposite sides to receive pins carried by arms 70 which are mounted upon a transverse pivot shaft 71 and extend upwardly through slots 72. Shaft 71 is disposed in a chamber 73 having communication with cylinder 65 through the slots 72 while an arm 74 connected to shaft 71 permits a suitable connection 74^a to the usual valve restoring mechanism. The needle is moved to closed position by pressure acting simultaneously on the rear end of plunger 64 and within chamber B. Admission of fluid pressure to chamber B is had through pipe 75, chamber 73, slots 72, cylinder 65 and a passage 75^a formed in the piston rod. Passage 75^a has communication at its forward end with chamber B, while its rear end terminates in a short passage extending laterally from the piston rod and having communication with cylinder 65. Admission of pressure to cylinder 65 causes a closing force to act on the rear end of plunger 64. Opening movement is had by exhausting fluid from chamber B and cylinder 65 and admitting fluid to chamber E as by pipe 76, and passages 77 and 78 formed respectively in the head of cylinder casing 65 and rod 67. Passage 78 terminates at the rear side of piston 68 in a short passage extending laterally to chamber E. Fluid flow through the pipes 75 and 76 can be controlled by a valve disposed in said pipes and operated either manually or by the governor. The restoring connection 74^a acts to restore the controlling valve to closed position after the needle 63 has moved any required amount.

Thus it is seen that my improved nozzle arrangement eliminates all need for having a tortuous passage in the branch pipes in order to permit operating mechanism to extend rearwardly therethrough. Certain results are that not only do I provide a smooth fluid passageway but in addition due to the elimination of curves a more economical pipe may be made. Further a relatively simple, compact and inexpensive nozzle is provided with self-contained operating means or servo-motors and one which may be easily controlled by fluid pressure.

50 As shown in Fig. 3, each runner has a single jet and more specifically these jets are supplied from a common supply conduit 45 having Y branch pipes 46 and 47, each of which terminates in nozzles 48 and 49. The needles for these respective nozzles are controlled by a usual form of controlling mechanism, including suitable servo-motors 50 and 51.

In Fig. 4 a double runner is shown, each runner having its own fluid supply casing 53 and 54 from which lead a series of circumferentially disposed nozzles such as shown in Fig. 2. The speed governor control 55 can be of any usual type known in the art and which includes usual restoring mech-

anism. The restoring mechanism may be connected to only one nozzle or to all and governing action may be limited to the nozzle or nozzles of only one runner, leaving the nozzles of the other runner to be independently controlled; or when conditions require it, the governor can be connected to operate simultaneously the valves controlling the pressure admission and exhaust for operating each needle, each of these control valves having its restoring connection from its needle.

As shown in Fig. 4 the two runners are relatively closely spaced, the vertical distance between the runners and between the two series of nozzles being reduced to a minimum. This not only results in a compact arrangement and minimum space requirement for the unit, but minimizes the loss of effective head on the upper runner due to the utilized free fall from that runner to the tailwater. In plants of moderate size or under high heads this loss will not be important since it will represent a very small percentage of the head, but in large units under comparatively low or moderate heads it is important to space the runners as closely as possible without, however, interfering with the free discharge from the upper runner or causing the discharge to be deflected upward against the buckets. In general the axial distance between runners can be considerably less than, or at most equal to, the outside diameter of the runners.

I claim:

1. A hydraulic impulse turbine bucket of the type adapted to receive a complete free jet and to discharge the same entirely to one side, comprising a body having a concave fluid-receiving surface of generally ellipsoidal form.

2. A hydraulic impulse turbine bucket of the type adapted to receive a complete free jet and to discharge the same entirely to one side, comprising an elongated body having a concave fluid-receiving surface receiving the jet from the narrow side of said elongated body, said surface terminating in upper and lower extremities which lie in substantially the same vertical plane.

3. A hydraulic impulse turbine bucket of the type adapted to receive a complete free jet and to discharge the same entirely to one side, comprising an elongated body having a concave fluid-receiving surface receiving the jet from the narrow side of said elongated body, said surface terminating in upper and lower extremities which lie in substantially the same vertical plane and one of said extremities comprising the discharge edge for said bucket.

4. A hydraulic impulse turbine bucket of the type adapted to receive a complete free jet and to discharge the same entirely to one side, comprising a body having a concave

fluid-receiving surface of generally ellipsoidal form, one portion of said surface terminating along a general area defining the entrance portion of said surface, while another portion of said surface terminates in a discharge edge lying substantially in a vertical plane containing said entrance area.

5. A hydraulic impulse turbine bucket of the type adapted to receive a complete free jet and to discharge the same entirely to one side, comprising a body having a concave fluid-receiving surface of generally ellipsoidal form, said body having an entrance opening and an entrance edge which lies generally in the plane of said opening.

10. A hydraulic impulse turbine bucket of the type adapted to receive a complete free jet and to discharge the same entirely to one side, comprising a body having a concave fluid-receiving surface with one of its axes elongated radially with respect to the axis about which the bucket rotates.

15. A hydraulic impulse turbine bucket of the type adapted to receive a complete free jet and to discharge the same entirely to one side, comprising a body having a concave fluid-receiving surface with one of its axes elongated radially relative to the axis about which the bucket rotates, and said fluid-receiving surface terminating at its upper and lower extremities in substantially the same vertical plane.

20. A hydraulic impulse turbine bucket of the type rotatable about a vertical axis and adapted to receive a complete free jet and to discharge the same entirely to one side, comprising a body having a concave fluid-receiving surface with one of its axes elongated radially with respect to said vertical axis, and said body having an entrance opening in the outermost radial upper portion thereof.

25. A hydraulic impulse turbine bucket of the type adapted to receive a complete free jet and to discharge the same entirely to one side, comprising a body having a concave fluid-receiving surface with an elongated radial axis, said bucket having an entrance opening, and an entrance edge adjacent said opening having substantially the same radial disposition as said opening.

30. A hydraulic impulse turbine bucket of the type adapted to receive a complete free jet lying substantially in a radial frame and to discharge the same entirely to one side, said bucket comprising a body having a concave fluid-receiving surface elongated radially relative to its axis of rotation and which in a radial section is substantially continuously curving between its inner and outer radial limits.

35. A hydraulic impulse turbine bucket of the type adapted to receive a complete free jet lying substantially in a radial plane and to discharge the same entirely to one

side, said bucket comprising a body having a concave fluid-receiving surface elongated radially relative to its axis of rotation and which in an axial section curves substantially continuously between its upper and lower vertical limits.

40. In a hydraulic impulse turbine bucket of the type which is rotatable about a vertical axis and adapted to receive a complete and substantially cylindrical free jet and to discharge the same entirely to one side, said bucket comprising a body having a radially elongated concave fluid-receiving surface elongated radially relative to its axis of rotation and which in horizontal section curves substantially continuously between its inner and outer radial limits and which in vertical section also curves substantially continuously between its upper and lower vertical limits, said vertical limits terminating in substantially the same vertical plane.

45. In a hydraulic impulse turbine bucket of the type which is rotatable about a vertical axis and adapted to receive a complete and substantially cylindrical free jet and to discharge the same entirely to one side, said bucket comprising a body having a concave fluid-receiving surface elongated radially relative to its axis of rotation and which in horizontal section curves substantially continuously between its inner and outer radial limits and which in vertical section also curves substantially continuously between its upper and lower vertical limits, and said vertical limits terminating in substantially the same vertical plane while an entrance opening is formed in the upper outermost radial portion of the bucket at the front thereof.

50. A hydraulic impulse turbine bucket of the type which is rotatable about a vertical axis and adapted to receive a complete free jet and to discharge the same entirely to one side, said bucket comprising a body having a concave fluid-receiving surface elongated radially relative to its axis of rotation and an entrance portion in the upper outermost radial portion thereof, the shape of said bucket being such that said surface has a greater degree of concavity in an outer radial portion thereof than at its inner radial portion.

55. A hydraulic impulse turbine comprising a vertical shaft and a plurality of simultaneously normally actuated impulse runners carried thereby, the uppermost runner having buckets adapted to discharge entirely directly downwardly.

60. A hydraulic impulse turbine comprising a vertical shaft and a plurality of simultaneously normally actuated downwardly discharging impulse runners disposed thereon and means whereby the discharge from the upper runner is free of interference with the lower runner.

17. A hydraulic impulse turbine comprising a vertical shaft and a plurality of simultaneously normally actuated downwardly discharging impulse runners disposed thereon, and means interposed between said runners whereby fluid from an upper runner is deflected out of the path of a lower runner. 5
18. A hydraulic impulse turbine comprising a vertical shaft, a plurality of downwardly discharging impulse runners disposed thereon, and means interposed between said runners whereby fluid from an upper runner is deflected away from the path of a lower runner, said deflecting means comprising a substantially cone shaped member. 10
19. A hydraulic impulse turbine comprising a vertical shaft, a plurality of downwardly discharging impulse runners disposed thereon, means interposed between said runners whereby fluid from an upper runner is deflected away from the path of a lower runner, and means forming a discharge passage surrounding the lower runner. 15
20. A hydraulic impulse turbine comprising a vertical shaft, a plurality of downwardly discharging impulse runners disposed thereon, means interposed between said runners whereby fluid from an upper runner is deflected away from the path of a lower runner, and means forming a chamber within which an upper runner is disposed and a discharging passage leading from said chamber around the lower runner. 25
21. A hydraulic impulse turbine comprising a vertical shaft, a plurality of downwardly discharging impulse runners disposed thereon, means interposed between said runners whereby fluid from an upper runner is deflected away from the path of a lower runner, means forming a chamber within which an upper runner is disposed and a discharging passage leading from said chamber, and means for controlling pressure within said chamber. 40
22. A hydraulic impulse turbine comprising a vertical shaft having a plurality of downwardly discharging impulse runners disposed thereon, and means for controlling the discharged fluid from an upper runner. 50
23. A hydraulic impulse turbine comprising a vertical shaft having a plurality of downwardly discharging impulse runners disposed thereon, means forming a tail water passage into which fluid flows from each runner, and means for controlling the discharged fluid from the upper runner whereby the lower runner may run free of the tail water level. 55
24. The combination with a fluid supply casing for a hydraulic impulse turbine, of a branch pipe leading therefrom intermediate the ends thereof and carrying a needle controlled nozzle mechanism at its outer end, 60
- the axes of said casing and branch pipe lying in a single plane and means for controlling said needle extending entirely laterally therefrom so that the rear inner portion of said nozzle mechanism is free from rearwardly extending operating mechanism. 70
25. The combination with a fluid supply casing for a hydraulic impulse turbine, of a branch pipe leading therefrom intermediate the ends thereof and carrying a needle controlled nozzle mechanism at its outer end, and means for controlling said needle extending entirely laterally therefrom so that the rear inner portion of said nozzle mechanism is free from rearwardly extending operating mechanism, whereby the axes of said branch pipe and nozzle lie in a substantially single plane and fluid may flow from said casing, through said branch pipe, and to said needle along a substantially smooth single curve. 75
26. A nozzle mechanism for forming a hydraulic impulse turbine jet comprising an outer casing having a tapering end piece provided with an orifice, a hollow casing disposed within said outer casing and held in spaced relation thereto for forming a fluid passageway therebetween, a movable valve member constituting a plunger having a slideable supporting relation with said internal casing to form a fluid operating chamber for said valve member, and a controlling arm movable with said plunger and extending laterally from said outer casing. 80
27. A hydraulic impulse turbine comprising a vertical shaft carrying a plurality of axially spaced impulse runners, said runners being proportioned in accordance with the head under which they respectively operate whereby they are adapted for simultaneous normal actuation. 85
28. A hydraulic impulse turbine comprising a vertical shaft carrying a plurality of axially spaced impulse runners adapted during normal actuation to rotate in the same direction, the lower of said runners being proportioned to operate normally under a higher head than the upper of said runners and each of said runners being so relatively proportioned that they are each adapted to operate during simultaneous actuation at their normal speed. 90
29. A hydraulic impulse turbine comprising a vertical shaft carrying a plurality of axially spaced impulse runners adapted during normal actuation to rotate in the same direction, the lower of said runners having a greater diameter than the upper thereof, whereby the same is adapted to operate under a higher head than the upper runner and each of said runners being so relatively proportioned that they are each adapted to operate during simultaneous actuation at their normal speed. 95

30. A hydraulic impulse turbine comprising a vertical shaft carrying a plurality of axially spaced impulse runners each discharging entirely downwardly and adapted during simultaneous normal actuation to rotate in the same direction and at the same speed, the lower runner having a larger diameter than the upper runner.

31. A hydraulic impulse turbine comprising a vertical shaft carrying a plurality of axially spaced impulse runners of different form whereby the lower of said runners is adapted to operate under a higher head than the upper runner, said runners each being adapted for driving forces in the same direction and at the same speed during simultaneous normal actuation.
